UNITED STATES PATENT OFFICE.

JOSEPH N. CAPECE, OF ASTORIA, NEW YORK.

COMBINED DOOR-LOCK-MOUNTING UNIT.

Application filed October 26, 1922. Serial No. 596,937.

To all whom it may concern:

Be it known that I, JOSEPH N. CAPECE, a citizen of the United States, residing at #351 Pierce Avenue, Astoria, Queens County, New York, and whose post-office address is #351 Pierce Avenue, Astoria, New York, have invented new and useful Improvements in Combined Door-Lock-Mounting Units, of which the following is a specification.

10 This invention relates to a combined door lock, casing and mounting therefor.

The object of the invention, generally stated, is to simplify the installation of locks on doors and minimize the cost of labor and expense in forming door panels and mounting locks thereon. To these ends I have devised a novel combined unit container and lock together with a door mount panel cooperating therewith, all of which 20 may be very quickly and easily assembled by the ordinary unskilled workman. In addition to the advantages and savings in cost of installation, my unit container may be produced on a quantity production basis 25 with the resultant economy in manufacture. Moreover, my improved lock installation has a finished appearance comparable in quality and degree with that of prior lock installations.

30 For a better understanding of the above indicated advantages and novel features of my invention and others which will herein-after appear, reference may be had to the accompanying drawings forming a part of 35 this application, wherein:

Fig. 1 is a side view of one modification of my invention.

Fig. 2 is a view on the line 2—2 of Fig. 1; and

40 Figs. 3, 4 and 5 respectively are perspective views of the lock, unit container and door mount.

Referring to the drawings where like numerals designate similar parts throughout, a door is illustrated having a side panel 1 on which is to be mounted a lock 2 which may be of any standard construction. My invention comprises as one element thereof a unitary finished container 3 which in the 45 specific embodiment shown is of elongated U-shaped form whose legs form the sides or plates 4 and 5, which are adapted to embrace, to fit over and bear snugly against the opposite sides of the door panel 1. The 50 side plates 4 and 5 are connected together by a web 6 (bend of the U member) and

this integral web 6 has an elongated rectangular opening 7 formed therein which is of the required dimensions and depth to receive the face plate 8 of the lock 2, the 60 face plate 8 and the web member 6 forming flushed surfaces with each other when in assembled position. The housing or unit 3 is provided with a finished keyhole opening 9 which registers with the keyhole 10 of the 65 lock and also with an opening 11 for the reception of the door knob spindle 12, this opening 11 being in register with the spindle opening 13 of the lock when in assembled position. The housing 3 is also provided with the attaching screw openings 14 which receive the screws 14' for entering the panel 1 at the points 15 and thereby retaining the housing unit 3 rigidly in the assembled position in the panel. The door 70 panel may be very simply and inexpensively formed with the transverse recess or opening 16 for the reception of the lock 2 when assembled in position, it being only necessary to chisel or saw out or otherwise form 80 such opening therein. The edge of the door panel is also formed with depressions or seats 17 adjacent the opening 16 for the reception of the ends of the face plate 8 of the lock 2, the depth of these seats 17 being 85 equal to the depth of the plate 8 in order to form a continuous flush surface along the door edge 18 when assembled. The face plate 8 is provided with the screw openings 90 19 for the reception of attaching screws whereby the lock 2 may be securely held 95 within the opening 16 by means of attaching screws 19' passing through the openings 19 and screwed on to the seats 17, the numerals 20 indicating screw openings registering with the openings 19 of the lock plate. The edges 21 of the housing unit 3 may be rounded off or otherwise finished to give the desired finished appearance and similarly 100 the openings 9 and 11 for the reception of the key and the door knob spindles may be also given the desired finish to furnish a good appearance. The openings 11 have formed therearound the sleeves 22 for the reception of the shanks 23 of the door knob, 105 these shanks abutting against the shoulder 24 formed around the bottom of these openings 11.

The housing 3 may, if desired, be provided with internal braces 24, such, for example, as the transverse plates 24 indicated in dotted lines which may be anchored in

any desired manner within the casing. Ordinarily the housing 3, however, is of sufficient rigidity and strength to obviate the necessity for any internal bracing. This housing 3 may be of any desired material, as metal or metallic composition. It is preferably of a metal which may be easily and economically stamped, formed and shaped into the desired construction in order to 10 minimize the cost of manufacture. The door panel may be of any standard construction and may have the opening 16 and seats 17 formed therein in the factory so that all that is required in the assembly of 15 my lock unit is to position the housing 3 upon the seats 17 and attach the screws 14' to the door thereby securely anchoring the housing 3 upon the seats 17 with the web member 6 flush with the edge of the door. 20 This may be done either separately or simultaneously with the positioning of the lock 2. The latter is simply positioned with its face plate within the opening 7 formed in the web member 6 and having the ends of 25 the face plate 8 resting against the seats 17 whereupon the screws 19' are inserted through the openings 19 and are screwed into the seats 17 at the points indicated by the numerals 20. After the door panel, 30 the housing and the lock are assembled in the manner indicated, the door knobs with their spindle 12 may be inserted through the openings 11 which register with the openings 13 of the lock. The door knobs are fastened to the spindle 12 in the usual manner, as indicated by the screws, or, if 35 desired, one of them may be formed integral with the spindle 12 with the other one detachable. My invention enables these

locks to be assembled on the door panels in 40 the very minimum of time with the consequent economy and saving in labor and expense. If it is not desired to have the door panels originally formed and cut to receive the combined lock unit, it is quite a simple 45 procedure to saw and chisel out the transverse opening 16 and form the seats 17 on the door edge. The assembled lock and mount, as indicated in Fig. 1, may be of the desired external finish and appearance 50 for use in the higher class houses, and the whole lends itself to harmony and neatness in design. Any desired finish or configuration may be given to my unit to suit the taste of the individual designer. 55

I claim:

1. A lock assembling and housing unit for door panels comprising an integrally formed member having two parallel side plates adapted to fit against the opposite 60 faces of a door panel and a vertical connecting web connecting the outer edges of said plates and adapted to rest in suitable grooves or recesses formed on the door edge to form a surface flush with the surface 65 of the door edge and said connecting web having a longitudinal opening for the reception of a door lock mechanism and face plate, the surface of the door edge, the connecting web and the face plate of the lock 70 mechanism being flush with each other.

2. A device of the character set forth in claim 1 wherein the parallel side plates are provided with bracing means therebetween. 75

In testimony whereof, I have signed my name to this specification.

JOSEPH N. CAPECE.
